(57) **CLAIM**

The ornamental design for a table saw, as shown and described.

DESCRIPTION

FIG. 1 is a front perspective view from the left side of a table saw showing our new design.

FIG. 2 is a front elevational view of the table saw.

FIG. 3 is a rear elevational view of the table saw.

FIG. 4 is a left side elevational view of the table saw.

FIG. 5 is a right side elevational view of the table saw.

FIG. 6 is a top plan view of the table saw; and,

FIG. 7 is a bottom plan view of the table saw.

In the above drawings, any broken line illustration is not part of the design sought to be patented.
